CURLING AND CRIMPING DEVICE

Cornelia Karasiewicz, Detroit, Mich.

Application January 6, 1936, Serial No. 57,815

4 Claims.

(Cl. 132—37)

This invention is an electric curling and crimping device designed for crimping such household articles as bed spreads and analogous coverings, window curtains and the like; and which can also be used for curling the hair.

The invention together with its objects and advantages will be best understood from a study of the following description taken in connection with the accompanying drawing wherein:

Figure 1 is a view partly in section and partly in elevation illustrating the crimping and curling device.

Figure 2 is a plan view of the device.

Figure 3 is a sectional view taken substantially on the line 3—3 of Figure 1.

Figure 4 is a side elevational view of a slightly modified form of the invention, and

Figure 5 is a sectional view taken substantially on the line 5—5 of Figure 4.

Referring to the drawing more in detail it will be seen that the device comprises a pair of shank members 5—5 crossed as shown and pivoted together as at 6. At the crossed portions thereof the shank members 5—5 are complementarily notched as at 7.

The shank members 5 have secured to one end thereof in any suitable manner and as indicated generally at 8 handles 9 of wood or other suitable material.

Secured to the shank member 5 at the end thereof remote from the handles 9, in any suitable manner, as for example, by being integral therewith are elongated longitudinally tapered jaw members 10.

The members 10 are hollow and accommodate electric heating elements in the form of resistance wires 11 embedded in suitable insulation 12 as shown.

The resistance wires 11 are electrically connected with the wires of an electric cord 13, the wires of the cord 13 extending through the handle 9, shanks 5 and are electrically connected with the resistance wires 11 within the jaws 10 as shown.

From the above it will be seen that thus far, the curling and crimping device has many features of the conventional hair curling iron, the exception being, that in accordance with the present invention the jaws 10 are identical insofar as the meeting faces of the jaws are formed for intimate contact one with the other as distinguished from the usual curling iron wherein one of the jaws is substantially cylindrical in cross section while the other jaw is substantially

semi-cylindrical in cross section and fits about the first jaw when the jaws are in closed position.

Further in accordance with the present invention each of the jaws 10 is longitudinally tapered throughout its entire length being of smallest diameter at the free end of the jaw.

Further in accordance with the present invention the jaws intermediate their respective ends and on their meeting faces are suitably formed to provide for a portion of the length of each jaw a roughened or toothed surface 14 whereby to provide for a positive grip of the jaws upon the article received therebetween whether that article be strands of hair, an article of wearing apparel, curtain, bedspread or the like.

In the form of the invention shown in Figures 1 to 3, as best shown in Figure 3 the jaws 10 are identical in cross section, each being substantially cylindrical throughout its entire length.

In the form of the invention shown in Figure 4 one of the jaws indicated by the reference numeral 10a is substantially cylindrical throughout its entire length while the other of the jaws indicated generally by the reference numeral 10b is substantially cylindrical for one-half of its circumference, and at opposite sides of the jaw the cylindrical surface of the jaw merges into flat surfaces 15 which converge toward the clamping face of the jaw and at said clamping face merge with a substantially flat clamping surface 16, the jaw 10b being of the cross sectional shape as best shown in Figure 5.

It is thought to be apparent, that in actual practice the heating elements 11 are arranged in a house circuit through the medium of the electric cord 13 in a conventional manner for heating the jaws of the device. The article to be crimped or curled, whether it be strands of hair, table cloth, bed cloth, a curtain or the like has a portion thereof clamped between the jaws and is held firmly between the jaws by reason of the engagement of the roughened or toothed surfaces 14 of the jaws with the article therebetween. In this manner a crimp or curl is put into the article as is clear to those skilled in the art.

From the foregoing it will be seen that I have devised a simple and economical electric curling or crimping device which may be used with equal facility for curling or crimping either the hair or household article such as bedspreads, curtains or the like.

In connection with the above the device is used for curling the hair as follows:

As will appear the device of the present in-

vention when used for curling hair is used substantially in the same manner as the well known type of hair curling tongs are used. Strands of hair at the end thereof are clamped between the jaw members 10 and the hair is then wound around the closed jaw members in an obvious manner. Within a comparatively short time the device is released and then with subsequent strands of hair the operation is completed, and by continuing such operations until the curling of all the hair has been completed a wave is given to the hair that will have a reasonable amount of permanency. Where a "tapered" wave in the hair is desired the device is held vertically, but for a "marcel" wave the device is applied horizontally, and for such a wave, instead of curling but several strands of hair at each operation as many strands of hair as possible is clamped therein between the jaws and then the device is given a half turn to the right and held in that position for a short period of time and then released. This operation is continued until all the hair has been so waved.

For crimping or ruffling materials such as curtain ruffles, bedspreads, the bottoms of dresses, etc. the following operation is performed. The material to be crimped or ruffled has a portion thereof placed between the jaws 10 and is gripped between the jaws, the jaws being brought together to securely clamp the material therebetween. Then the left hand of the operator is placed on the material to hold the material more or less taut while with the right hand the crimping device is given a half turn to the right and held in that position for a short period of time after which the device is released and on a next adjacent portion of the article the operation just described is repeated.

These operations are continued until the crimping or ruffling of the article, or desired parts thereof has been completed. When completed a well tapered ruffle is presented, the tapering ruffle being narrow at the top and wide at the bottom thus giving a natural appearance to the crimped or ruffed portion of the article. In this connection it will be understood that but the edge portions of bedspreads, curtain trimmings, or valances are ruffled or crimped for adding to the attractive appearance thereof.

It is thought that a clear understanding of the manner of using the device will be had from the foregoing.

Having thus described the invention, what is claimed as new is:

1. An electric curling and crimping device comprising a pair of crossed shank members pivoted together, elongated longitudinally tapered jaw members on one end of said shanks, said jaws being hollow, electric heating elements arranged in said jaws, said jaws having inter-fitting roughened areas on their meeting surfaces to effect a positive hold on the article clamped therebetween.

2. An electric curling and crimping device comprising a pair of crossed shank members pivoted together, elongated longitudinally tapered jaw members on one end of said shanks, said jaws being hollow, electric heating elements arranged in said jaws, said jaws having inter-fitting roughened areas on their meeting surfaces to effect a positive hold on the article clamped therebetween, and handles on said shanks at the ends thereof from said jaws.

3. An electric curling and crimping device comprising a pair of crossed shank members pivoted together, elongated longitudinally tapered jaw members on one end of said shanks, said jaws being hollow, electric heating elements arranged in said jaws, said jaws having inter-fitting roughened areas on their meeting surfaces to effect a positive hold on the article clamped therebetween, handles on said shanks at the ends thereof remote from said jaws, said jaws being substantially cylindrical in cross section throughout their respective lengths.

4. An electric curling and crimping device comprising a pair of crossed shank members pivoted together, elongated longitudinally tapered jaw members on one end of said shanks, said jaws being hollow, electric heating elements arranged in said jaws, said jaws having inter-fitting roughened areas on their meeting surfaces to effect a positive hold on the article clamped therebetween, handles on said shanks at the ends thereof remote from said jaws, one of said jaws being substantially cylindrical throughout its entire length, and the other of said jaws being substantially segmentally shaped in cross section and having flat surfaces on substantially three sides thereof, one of said surfaces constituting a gripping surface and adapted to bear against the other of said jaws for effecting a gripping action between the jaws.

CORNELIA KARASIEWICZ.
